MAGAZINE BINDER

Herman T. Arends, Highland Park, Mich.

Application August 7, 1940, Serial No. 351,659

1 Claim. (Cl. 281—36)

The present invention relates to magazine binders.

Among the objects of the invention is a binder especially suitable for use with single fold magazines, though other types may be bound therein.

Another object is a binder which shall be economical to make, easy to use, and one which presents a good appearance.

Other objects and advantages will be apparent from the following description and the accompanying drawing in which

Figure 1 is a sectional view through a binder of the present invention containing its complement of magazines.

Figure 2 is a longitudinal section through the back portion of the binder and a magazine.

Figure 3 is a partial end view in perspective, and

Figure 4 is a perspective view of a detail of construction.

In producing the binder, two strips of stiff fiber board or other suitable material, one slightly shorter than the other, are fastened together, preferably with suitable adhesive tape, as shown in Figure 4, in which 10 and 11 are the strips and 12 the tape.

These strips are used to form the back of the volume and may be left flat or may be curved. In either case the strip assembly and two cover boards 15 are covered with suitable fabric 16, such as cloth, imitation leather, etc., and the strips further secured to the boards 15 by the hinge fabric 17. The boards are then suitably lined as at 18.

Over the inner surface of the thus prepared assembly is fixed a strip of suitable cloth 20 of a width somewhat greater than the width of the strips 10 and 11 and having its edges 21 gummed.

This cloth strip 20 is, as shown, extended lengthwise of the strips 10 and 11 and with the gummed edges left free.

After the assembly has been completed, the cover fabric 16 is slit at the ends of strip 11, as at 25, allowing access to the space between the strips 10 and 11.

In using the binder, a suitable cord 30, or wire, or other filament, is first passed through the openings 25 in the back and between strips 10 and 11 and then tied or otherwise fixed through the center fold of a magazine 35 as indicated in Figures 1 and 3.

The gummed edges 21 of cloth strip 20 are used on the first and last of the magazines to maintain the group against lateral displacement. When the full complement of magazines is attained, the volume, because of the rigid back, is resistant to rough handling and may be treated as a regularly bound book.

Now having described the invention, what I claim is:

A binder for magazines or the like consisting of covers and a back portion permanently hinged thereto, said back portion consisting of stiff members, one overlying and somewhat shorter than the other, the said members being fixed together at their lateral edges, with the shorter one innermost with respect to the combined device, a fabric hinge piece overlying said members and secured thereto and having its lateral edges fixed to said covers and a fabric cover sheet extending over the covers and fixed to said back members in such fashion as to allow access to the end of said short member and permit the passage of cords and the like lengthwise between the back members.
